EDWARD LIONEL JOSEPH, OF LONDON, ENGLAND.

APPARATUS FOR OZONIZING ATMOSPHERIC AIR.

No. 829,790.

Specification of Letters Patent.

Patented Aug. 28, 1906.

Application filed December 12, 1905. Serial No. 291,400.

To all whom it may concern:

Be it known that I, EDWARD LIONEL JOSEPH, electrical engineer, a subject of the King of Great Britain, residing at 27 Chancery Lane, London, England, have invented an Improved Apparatus for Ozonizing Atmospheric Air, of which the following is a specification.

This invention relates to apparatus for ozonizing atmospheric air by the silent discharge of a high-tension electric current; and it has for its object more particularly to provide a compact, self-contained, and portable machine which shall be free from liability to cause annoyance by the transmission of vibrations and wherein all the moving parts are so housed as to be inaccessible to unauthorized persons.

The apparatus may be used with either an alternating or a direct current, a motor-transformer being in the latter case employed to convert the direct current into an alternating current. In the following description it is assumed that the apparatus is used with a source of direct-current supply.

In the accompanying drawings, which illustrate the preferred form of the apparatus, Figure 1 is a longitudinal vertical section of the machine, and Fig. 2 is a perspective view of the same, parts being broken away in the latter figure to show the construction. Fig. 3 is a diagram of the electrical connections.

1 is the outer casing of the apparatus, consisting of a rectangular wooden box, whereof the rear end is closed by a filter or drying medium 2 for the air which through it enters the apparatus, this filter being formed of a layer of cotton-wool or other suitable material inclosed in a wirework-frame attached to the casing 1 around the rear opening of the latter and which if hinged thereto would be secured by a lock. The opposite or front end of the casing 1 is covered by an open screen 3, of wirework, likewise secured to the casing and adapted while giving passage to the air issuing from the apparatus to prevent access to the interior of the latter by unauthorized persons.

50 In the interior of the casing 1 is fixed a transverse partition 4, having a circular aperture 5 of relatively large area, wherein an air-propelling fan 6 is mounted to rotate upon a horizontal axis in such a direction as 55 to cause atmospheric air to be drawn into the casing through the filter 2 and expelled,

as hereinafter explained, through the screen 3. The fan 6 is driven by means of an electric motor 7, upon whose shaft it is mounted, the body of the motor being mounted within 6c the rearward compartment 8 of the two compartments into which the casing is divided by the partition 4.

Extending longitudinally of the casing within the lower part but above the bottom 65 of the front compartment are a pair of horizontal rails 9, which may be fixed at their rear ends to the partition 4 and at the forward ends to a cross-bar 10, stretching across the front end of the casing. The rails 9 serve 70 to support a rectangular wooden box 11, which may be open at its front end and which has an outwardly-projecting back 12 of pyramidal or equivalent shape adapted to cause the current of air propelled against it 75 by the fan 6 to be divided and deflected so as to pass around the top, bottom, and sides of the box 11 on its way to the front screen 3. Within the box 11 (which is made of a size suitable for the purpose) is placed a step-up 80 transformer 13, the box being movable in the fore-and-aft direction upon the rails 9, so that the distance of the rear end 12 of the box from the fan 6 may be adjusted as may be found most suitable, and the weight of the 85 transformer serving to maintain the box in the position wherein it may be set.

The electrodes over which the high-tension alternating current is led from the step-up transformer 13 are in the form of four separate panels A B C D, fastened together so as to form a rectangular structure open at the front and rear ends and mounted so as to extend longitudinally of the front compartment of the casing 1, the panels A B C D, 90 which surround at a distance the top, bottom, and sides of the box 11, being supported about midway between said box and the outer casing 1, as indicated. The air thus finds its way from the fan 6 to the delivery-screen 3 by way of two concentric passages, which are separated from one another by the electrode-panels, the outer and inner passages being bounded by the casing 1 and the box 11, respectively. Each panel comprises a pair of electrodes 14 15, formed each of a sheet of non-oxidizable metal gauze, the two sheets of gauze being placed at opposite sides of a suitable dielectric consisting, preferably, of a sheet of mica and the whole being 100 clamped between a pair of outer and inner rectangular wooden frames 14^a 15^a, the

sheets of gauze being securely held by their margins being clamped in grooves on the inner faces of the respective frames by means of strips of wood 14^b 15^b.

- 5 The assemblage of panels A B C D may be detachably secured together in any convenient manner—as, for example, by cords 16 bound around the four frames close to their front and rear ends, as shown, and the structure thus formed is suspended from the top of the casing 1 by springs 17, which are themselves dependent from india-rubber cushions 18, so that vibrations set up in the panels shall not be transmitted to the casing.
- 15 Referring to the diagram of electrical connections, Fig. 3, current is led to the fan-motor 7 from a suitable source 19 of direct current through a switch 20, which also serves to control the supply of direct current to a 20 motor-transformer 29, (placed outside the casing 1 and at any distance therefrom,) whereby the current supplied to the step-up transformer 13 is converted into an alternating current of higher voltage. 32 is a rheo- 25 stat or regulating-switch interposed in the circuit between the motor-transformer 29 and the switch 20. It is mounted upon the casing 1 in convenient proximity to the switch 20 and serves, by regulating the current 30 passed through the motor-transformer 29, to correspondingly vary the strength of the stream of ozone discharged from the apparatus.

The switch 20 has two operative positions, 35 in the first of which (indicated by the dotted line at 20^a, Fig. 3) it closes the circuit of the fan-motor 7 alone. The fan being thus started, the switch 20 may be moved to the second or final position, (indicated by the dotted line at 20^b,) wherein it closes the circuits 40 of both the fan-motor 7 and the motor-transformer 29, the latter of which is thus permitted to start, but only at a slow speed, so long as the regulating-switch 32 is in position to 45 maintain a high resistance in the circuit. The regulating-switch 32 may then be adjusted at will, so as to permit of any desired increase in the speed of the motor-transformer 29 and in the output of ozone.

50 It will be obvious that the arrangement above described might be simplified by making the fan-motor 7 serve the additional purpose of a transformer for converting the direct current into an alternating current, in 55 which case the separate motor-transformer 29 would be dispensed with. The high-tension current from the step-up transformer 13 is distributed over the sheets of gauze 14 15, forming the panels A B C D, by means of conductors formed, preferably, of metal rods 60 spanning the width of the panels, there being a pair of rods 21 22 extending across and in contact with the outer surface of each outer layer 14 of gauze, and a similar pair 23 24 extending across and in contact with the inner

surface of each inner layer 15. Current is led from one terminal 25 of the transformer by a wire 26 to one end of the first rod 21 on the outer sheet 14 of the first panel A, whence the current passes to the second rod 22 on the same outer sheet. From this the current is led by a wire to the first rod 21 of the outer sheet 14 of the second panel B, whence it passes to the second rod 22 on the same sheet, and so on with each panel. The current is similarly led by a wire from the other terminal 28 of the transformer 13 by a wire 27 to one end of the first rod 24 on the inner sheet 15 of the first panel A, whence the current is led so as to traverse the inner sheets of the three remaining panels B, C, and D in a similar manner to that described above with reference to the outer sheets 14 of the panels. A silent or condenser discharge is thus caused to take place over the entire inner and outer surface of each panel A B C D, the air propelled by the fan becoming ozonized in its passage over said surfaces on its way to the exit-screen 3.

It will be obvious that in cases where an 90 alternating current is available the motor-transformer 29 will not be required, the alternating current being led from the source of supply direct to the step-up transformer 13.

I claim—

1. Apparatus for ozonizing atmospheric air by the silent discharge of a high-tension electric current comprising an outer casing forming a passage for the air provided with an air-propelling fan; means for deflecting 100 and guiding the current of air during the ozonizing operation, consisting of an inner casing serving to contain an electrical transformer; and a plurality of pairs of electrodes secured together to form a hollow structure 105 open at both ends and disposed between and at a distance from said inner and outer casings, the electrodes of each pair of electrodes having a dielectric between them, substantially as specified.

2. A portable self-contained apparatus for ozonizing atmospheric air, consisting essentially of an outer casing inclosing an air-propelling fan; an electrical transformer; pairs of electrodes secured together and forming 110 passages for the air to be ozonized, the electrodes of each pair of electrodes having a dielectric between them, and connections between the electrodes and transformer; said apparatus being provided at one end with a filter for the entering air and at the other end with an apertured screen serving to prevent access to the interior of the casing, substantially as described.

3. An apparatus for ozonizing atmospheric air by the silent discharge of a high-tension electric current, comprising an outer casing forming a passage for the air provided with an air-propelling fan, means for deflecting 115 and guiding the current of air during the 120

ozonizing operation, consisting of an inner casing serving to contain an electrical transformer, and a plurality of pairs of electrodes fastened together to form a hollow structure open at both ends and disposed between and at a distance from said inner and outer casings, the electrodes of each pair of electrodes

having a dielectric between them, and springs for supporting the open-ended electrode structure, for the purpose specified.
